DESIGN FOR A DISPLAY BOX

Reginald A. Nagle, Rochester, N. Y., assignor to Flower City Specialty Company, Rochester,
N. Y., a corporation of New York

Application December 5, 1939, Serial No. 88,684

Term of patent 14 years

To all whom it may concern:

Be it known that I, Reginald A. Nagle, a citizen of the United States, residing at Rochester, in the county of Monroe and State of New York, have invented a new, original, and ornamental Design for a Display Box, of which the following is a specification, reference being had to the accompanying drawing, forming part thereof.

Fig. 1 is a side elevational view of a display box, showing my new design;

Fig. 2 is a top plan view thereof, and

Fig. 3 is a perspective view thereof.

I claim:

The ornamental design for a display box, substantially as shown.

REGINALD A. NAGLE.
